UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed August 23, 1926. Serial No. 18,807. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dresses, of which the following is a specification, reference being had to the accompanying drawings, forming part thereof, wherein the dress is distinguished by the form of plaited skirt and the ornamental features of the garment at the waist, collar, and cuffs.

I claim:

The ornamental design for a dress, as shown.

TAUBE DAVIS.
